EXHAUST-STEAM INJECTOR

Application filed September 6, 1929. Serial No. 390,818.

Our invention relates to exhaust steam injectors of the type adapted to be ordinarily operated by exhaust steam from an engine and to be operated wholly by live steam from a steam generator when such exhaust steam is not available.

Injectors of this character find their widest use as applied to steam locomotives, where the majority of the factors affecting their operation are subject to wide variation. In order to be most effective, the injectors must provide a relatively wide range of water feeding capacity and must be able to operate over this range under widely different conditions of suction water temperature, boiler steam pressure and exhaust steam pressure.

We have found that both the efficiency and the operating range of injectors of this type may be materially increased if the pressure of the low pressure steam admitted to the injector, whether it be exhaust steam from an engine or live steam from a boiler, is closely regulated so that a substantially constant pressure is maintained at the entrance of the low pressure steam nozzle.

In prior forms of exhaust steam injectors, the live steam used to supplant exhaust steam when the latter is not available (which live steam will hereinafter be referred to as auxiliary steam) has been obtained by passing high pressure steam from the boiler through an orifice or choke which serves to reduce its pressure to substantially that of the average exhaust steam pressure used. This arrangement, however, has several distinct limitations. In the first place, fluctuations in boiler pressure, which are frequently of considerable magnitude, are reflected in the pressure of the auxiliary steam after it has passed through the choke. In the second place it is common practice to employ different sized nozzles in the same injector body in order to obtain different injector capacities, and the area of the auxiliary steam choke must be altered for each specific size of nozzle if the desired auxiliary steam pressure at the nozzle is to be obtained. In practice this often leads to difficulties due to errors which result in attempting to use nozzle and choke sizes which are not intended to be used together.

It is the general purpose of the present invention to increase the injector efficiency and range by automatically regulating the exhaust steam and auxiliary steam supplies to the injector to secure a substantially uniform constant steam pressure under all operating conditions at the low pressure nozzle of the injector. A further purpose of the invention is to reduce the pressure of the auxiliary steam in a novel manner which eliminates the necessity for using chokes of different area with different sizes of nozzles. A still further purpose of the invention is to effect regulation of both exhaust steam and auxiliary live steam automatically through the medium of a single pressure regulating mechanism.

With the above and other purposes in view, the invention may best be understood by reference to the accompanying drawings illustrating a preferred form of apparatus for carrying the invention into effect, in which Fig. 1 is a fragmentary elevation of a locomotive having an injector embodying the invention applied thereto, and Fig. 2 is a fragmentary central vertical section on an enlarged scale of the part of the injector illustrating the principles of the invention.

Referring now to Fig. 1, the injector which is of the general form disclosed in our co-pending application Serial No. 390,817, filed September 6th, 1929, is indicated generally at A, said injector being supplied with water through the pipe 1 and with live steam for operating the injector and its control system through pipe 2, which leads from the engine turret 3 and has located therein a shut-off valve 4. Exhaust steam is supplied to the injector through pipe 5 leading from the engine cylinders (not shown) and water delivered by the injector passes through pipe 6 to the boiler check valve (not shown).

A main live steam control valve B (Fig. 2), operated through the medium of the control lever 7 located in the engine cab, serves to admit live steam to the injector and control system and the admission of auxiliary steam to the injector is controlled by the automatic valve C (Fig. 2), the latter in turn being under the influence of an exhaust steam actuated diaphragm valve indicated at D and

connected with valve C by means of pipe 8. Exhaust steam for actuating valve D is supplied thereto through the pipe 9 leading from the engine exhaust pipe.

Referring now more particularly to Fig. 2, the injector A comprises a main low pressure steam nozzle 10 supplied from the low pressure steam chamber 11 of the injector and a high pressure steam nozzle 12 through which a small quantity of steam is admitted at high pressure (such steam being hereinafter referred to as supplementary steam) at all times when the injector is in operation. The injector is further provided with the usual water cone, and combining and delivery tubes which form no part of the present invention and need not be described in detail herein.

The main steam valve B comprises a pressure actuated valve member 13 adapted to be opened by steam pressure against the action of the spring 14 upon the release of pressure from chamber 15 above the pilot valve piston 16. Such release is effected through a relay valve (not shown) which vents pipe 17 upon proper manipulation of the control lever 7. This mechanism is fully described in our co-pending application above referred to. The specific form and manner of operation of valve B are not germane to the present invention, and any desired equivalent valve may be employed.

High pressure live steam is admitted to the chamber 18 upon the opening of the main steam valve and from this chamber passes directly to nozzle 12. Chamber 18 is placed in communication with the conduit 19 by means of port 20 controlled by the automatic valve C. The latter comprises a valve member 21 to which is attached piston 22, the latter having formed thereabove a chamber 23 adapted to be maintained under pressure by leakage through passage 24 in piston 22 or to be vented through pipe 8 by the exhaust steam control valve D. When the engine is operating and exhaust steam is available pipe 8 is closed, which causes pressure to be built up in chamber 23, balancing piston 22, and live steam pressure in chamber 18 operates to close valve 21. If exhaust steam is not available, pipe 8 is vented, and the unbalanced pressure on piston 22 operates to open valve 21 and admit high pressure live steam to conduit 19. The specific details of the valve mechanism D are also disclosed in our co-pending application already referred to and need not be described in detail here.

The admission of exhaust steam and auxiliary live steam to the low pressure steam chamber 11 of the injector is controlled by an exhaust shut-off valve E and a regulating valve F. Valves E and F may be advantageously carried in a separate housing 25 interposed between the injector body and the exhaust pipe 5, valve F being arranged between valve E and the injector.

Exhaust valve E comprises a single seated valve member 26 mounted on arm 27 which is pivoted about pin 28 so that the valve member 26 may swing open from its seat in the direction of exhaust steam flow. A lever 29 is also pivoted on pin 28 independently of arm 27, said lever having a boss 30 thereon adapted to engage the exhaust valve assembly to close the latter valve when the lever is urged to the right by piston 31, the latter being under the influence of a relatively heavy coil spring 32 suitably retained in housing 25. The lower end of lever 29 is engaged on the side opposite piston 31 by a second piston 33, the latter being located in a steam chamber 34 connected by conduit 35 with the high pressure steam chamber 18 of the injector.

The operation of valve 26 is largely obvious. Whenever the injector is shut off, valve 26 is held to its seat by the action of spring 32 to prevent exhaust steam from the engine reaching the injector. As soon as the injector control valve is opened, piston 33 over-balances spring 32 due to the admission of high pressure steam from chamber 18 to chamber 34 and valve 26 is then free to open if there is sufficient exhaust steam present in pipe 5 to overcome whatever pressure may be present in the steam space 36 between the valve 26 and the regulating valve F.

The regulating valve F comprises a double seated valve member 37 adapted to close vertically against seats formed in a suitable web 38, said valve member being guided at the bottom in a suitable cylinder 39 and at the top by an annular guide 40 forming part of the closure member 41. The valve member 37 is urged to open position by the coil spring 42, the upper end of which bears against a transverse web 37^a formed in member 37. Member 41 is covered by a cap 43 forming a chamber 44 in which is located a resilient diaphragm member 45, preferably of the bellows type. At its lower end bellows 45 is secured to an annular plate 46 clamped between member 41 and cap 43 and at its upper end to a plate 47. Plate 47 is rigidly secured to the upper end of a regulating spindle 48 sliding in the annular guide 40 and abutting at its lower end against the transverse web 37^a of the valve member 37. The chamber formed inside the bellows 45 is preferably vented by means of a passage 49 which allows leakage past the spindle 48 to pass to the atmosphere. The closed chamber 44 formed by the cap 43 and the bellows assembly is connected by means of the conduit 50 to the outlet side of the regulating valve 37.

The operation of this valve is as follows: When the pressure on the outlet side of this valve, which is substantially the pressure existing in chamber 11, is at or below the desired working pressure, valve 37 is held in its wide open position by spring 42. If, however, the

pressure on the outlet side of the valve tends to increase above the desired value, this increase in pressure is transmitted through conduit 50 to chamber 44 where it acts to compress bellows 45 and move valve 37 toward closed position against the action of spring 42.

Auxiliary steam is carried through pipe 19 to the steam space 36 between the valves E and F, passing into this space through a fixed 10 orifice 51. The size of this orifice is such that when the boiler pressure falls to the lowest value at which injector operation can be maintained, the reduction in pressure of steam passing through the orifice will provide steam at least above atmospheric pressure in chamber 36. This means that under 15 normal boiler pressure conditions, the pressure of the steam admitted through choke 51 to chamber 36 will be considerably above that at which it is desired to use it in the injector.

Under practical operating conditions, the most desirable pressure to be maintained in chamber 11 will ordinarily be somewhere between 6 and 10 pounds gage pressure while the exhaust steam pressure encountered in actual practice will vary from zero gage pressure to 35 pounds. A choke 51 which will reduce the auxiliary steam pressure to the proper pressure for use in chamber 11 from a very low boiler pressure of say 100 pounds per square inch or less, will, under a normal boiler pressure of say 240 lbs., reduce the pressure of the steam entering chamber 36 to about 35 pounds per square inch, which is approximately the same as the maximum exhaust steam pressure encountered in practice. It will therefore be seen that the pressure regulating valve F will with this arrangement have to handle a maximum steam pressure of about the same value whether the steam is exhaust or auxiliary, and therefore a single pressure reducing arrangement will serve to regulate both exhaust steam and auxiliary steam pressures.

In the embodiment illustrated, the regulating valve is controlled by the pressure on the outlet side thereof, but it will be obvious that a regulating valve actuated in accordance with variations in the inlet pressure may be employed, and it will further be evident that valves E and F may, if desired, be combined in a single structure with the choke orifice 51 located between the shut-off portion of such valve and the regulating portion thereof. The form shown, however, is to be preferred, particularly with respect to controlling the regulating valve from the discharge side, as with this arrangement close regulation of the pressure in chamber 11 is more readily obtained.

The operation of the apparatus as a whole may be briefly summarized as follows: Assuming the injector to be shut off, the several parts will be in the positions shown in Fig. 2.

Upon opening of the main valve B by manipulation of the control lever 7, steam passes simultaneously to the supplementary nozzle 12 and to chamber 34 to free the exhaust valve member 26. If the engine is running at this time and exhaust steam is available, vent pipe 8 leading from the automatic valve C is closed by the exhaust steam control valve mechanism D, with the result that the valve member 21 remains closed. Exhaust steam from supply pipe 5 opens valve member 26 and the pressure of the exhaust steam passing from chamber 36 to chamber 11 is regulated by the valve F.

Upon closure of the engine throttle, the failure of the exhaust steam supply causes the valve mechanism D to open vent pipe 8 and permit valve 21 to be opened by steam pressure in chamber 18. High pressure steam then flows through conduit 19 and the choke 51 to chamber 36. Assuming normal boiler pressure to exist, the pressure in chamber 36 will be in the neighborhood of 35 pounds per square inch, which pressure will close the exhaust valve member 26, and the pressure of the steam supplied from this chamber to chamber 11 of the injector will be suitably reduced to the constant pressure desired by passing through the regulating valve F.

It will thus be seen that with the above described arrangement a substantially constant pressure is maintained in the low pressure steam chamber 11 at all times regardless of fluctuations in either exhaust steam pressure or in boiler pressure.

We claim:

1. In the operation of an injector having a high and low pressure element, supplying steam at low pressure to the low pressure element of the injector from the exhaust of a steam engine when it is working and from a steam generator when the engine is not working and regulating automatically the pressure of the steam supplied to the low pressure element of the injector from either the steam generator or exhaust to obtain a substantially constant pressure within the low pressure element irrespective of the higher pressure obtaining in the steam generator or of variation in exhaust pressure.

2. In the operation of an injector having a high and low pressure element, supplying steam at low pressure to the low pressure element of the injector from the exhaust of a steam engine when it is working and from a steam generator when the engine is not working and regulating under the influence of exhaust pressure the pressure of the steam supplied to the low pressure element of the injector from either the steam generator or exhaust to obtain a substantially constant pressure within the low pressure element irrespective of the higher pressure obtaining in the steam generator and of variation in exhaust pressure.

3. In the operation of an injector having a high pressure element and a low pressure element, supplying steam at high pressure to the high pressure element, controlling the supply of steam at high pressure, supplying steam at low pressure to the low pressure element of the injector from the exhaust of a steam engine when it is working and from a steam generator when the engine is not working and regulating the pressure of the steam supplied to the low pressure element of the injector from either the steam generator or exhaust to obtain a substantially constant pressure within the low pressure element independently of the control of the supply of steam at high pressure and irrespective of the higher pressure obtaining in the steam generator or of variation in exhaust pressure.

4. In the operation of an injector having a high and low pressure element, supplying steam at low pressure to the low pressure element of the injector from the exhaust of a steam engine while it is working and from a steam generator when the engine is not working and so regulating the flow of steam to the low pressure element from either the generator or exhaust with relation to the pressure obtaining in the generator or to exhaust steam available as to maintain a continuous supply of steam to the low pressure element at a substantially constant pressure irrespective of the higher pressure obtaining in the generator or of variation of exhaust pressure.

5. The method of supplying low pressure live steam from a high pressure steam generator to an exhaust steam injector having means for utilizing exhaust steam and low pressure live steam in alternation, which consists in first reducing the pressure of the high pressure steam from the generator to an intermediate pressure materially lower than the pressure in the generator by passing said steam through a fixed orifice and subsequently further reducing and regulating the pressure of said steam to maintain a substantially constant pressure at said means.

6. An exhaust steam injector comprising a low pressure steam chamber, means for admitting exhaust steam and auxiliary live steam to said chamber through a common inlet, a regulating valve for admitting steam through said inlet at substantially constant pressure, means for admitting exhaust steam to said regulating valve when exhaust steam is available, and means for admitting auxiliary live steam to said regulating valve at a pressure above the regulated pressure when exhaust steam is not available.

7. An exhaust steam injector comprising a chamber to which low pressure steam is admitted, a conduit for supplying exhaust steam to said chamber, an exhaust steam shut-off valve in said conduit, a regulating valve in said conduit between the shut-off valve and the injector for delivering steam

to the injector at substantially constant pressure, and means between the valves for admitting auxiliary live steam to said conduit when exhaust steam is not available.

8. An exhaust steam injector comprising a chamber to which low pressure steam is admitted, a conduit for supplying exhaust steam to said chamber, an exhaust steam shut-off valve in said conduit, a regulating valve in said conduit between the shut-off valve and the injector for delivering steam to the injector at substantially constant pressure, means between the valves for supplying live steam from a high pressure source to said conduit, and means for partially reducing the pressure of said live steam before it reaches said conduit.

9. An exhaust steam injector comprising a low pressure steam chamber, a conduit for supplying exhaust steam thereto, a shut-off valve in said conduit, a pressure regulating valve in said conduit between the shut-off valve and the injector, said regulating valve acting in response to pressure on the discharge side thereof to maintain a substantially constant pressure in said chamber, and a conduit for supplying auxiliary live steam to said regulating valve when exhaust steam is not available.

10. An exhaust steam injector comprising a low pressure steam chamber, a conduit for supplying low pressure steam thereto, a pressure regulating valve located in said conduit and adapted to regulate the pressure of steam passing therethrough to maintain a substantially constant pressure in said chamber, a valve controlled pipe for supplying exhaust steam from an engine to said conduit on the inlet side of said regulating valve, a connection for admitting auxiliary live steam from a steam generator to said conduit on the inlet side of the regulating valve, and means forming a choke in said connection for reducing the pressure of the steam passing therethrough when the generator is operating at normal pressure to a value within the pressure range at which exhaust steam is normally supplied from the engine.

11. An exhaust steam injector comprising a low pressure steam chamber, a conduit for supplying low pressure steam to said chamber, a regulating valve located in said conduit and adapted to regulate the pressure of steam supplied thereto to maintain a substantially constant pressure in said chamber, and means for supplying exhaust steam from an engine and auxiliary live steam from a generator in alternation to the inlet side of said regulating valve.
